EASY OPENING CONTAINER

Filed July 20, 1929

Fig 1

UNITED STATES PATENT OFFICE

FRANK J. O'BRIEN, OF NEW YORK, N. Y., ASSIGNOR TO CONTINENTAL CAN COMPANY, INC., OF NEW YORK, N. Y., A CORPORATION OF NEW YORK

EASY OPENING CONTAINER

Application filed July 20, 1929. Serial No. 379,824.

The invention relates to new and useful improvements in easy opening containers and more particularly to a hermetically closed container wherein the ends are secured 5 to the body portion by double seaming.

An object of the invention is to provide an easy opening container of the above type wherein the body portion is provided with score lines adjacent one end thereof for separating the end from the body with an inserted collar which maintains the full capacity of the container when it is open and with a member for an outside slip reclosure, the lower edge of which is smooth and unbroken.

10 A further object of the invention is to provide an easy opening container of the above type wherein the member carried by the detached end and used for an outside slip in reclosing is formed integral with the end.

In the drawings which show by way of illustration one embodiment of the invention:

25 Fig. 1 is a sectional view through a container embodying the improvements.

Fig. 2 is a sectional view through the container showing the end as released from the body and removed therefrom.

30 The invention broadly is directed to an easy opening container made of metal wherein the body portion adjacent one end thereof is scored so as to provide a tearing strip which may be removed for separating 35 the end from the body. Located within the body and fixed thereto is an inserted collar. This inserted collar is attached to the body beneath the lower score line and extends upwardly into substantial contact with the 40 inner face of the end. The portion of the collar from the lower score line to the upper end thereof is inset. The end is provided with a member which is adapted to slip down over the upper portion of the collar 45 which is attached to the body of the con-

tainer. Said outside slip member is provided with a rounded smooth unbroken edge. As shown in the present embodiment of the invention this member fixed to the end is formed integral therewith. This is accomplished by a drawing process. When the tearing strip is removed the end is released from the body and may be removed. When it is removed the capacity of the container is not in any way changed. This integral member fixed to the end makes an outer slip engagement with the collar on the body and this produces a very efficient reclosing cover for the container after it is opened.

50 Referring more in detail to the drawings, the improved container includes a body portion 1 made in the usual manner from a blank, the edges of which are joined in a side seam. Attached to the body are closing ends which are secured thereto preferably by double seaming. The upper end is indicated in the drawings at 2 and the double seam for joining the upper end to the body is indicated at 3. So far as the closing of the container is concerned, the features shown are of the usual construction. The container body is of uniform diameter throughout and can be made on any standard body maker. The ends are secured to 55 the body by the ordinary double seam which can be made on any standard double seaming mechanism. The body wall is provided with a lower score line 4 and an upper score line 5. Between these score lines is 60 the tearing strip. This tearing strip may be made in any suitable way and one or more score lines may be used or any other way provided for weakening the body wall so that a strip may be torn out. The strip 65 is indicated at 6. When this strip is torn out the end is released from the body. This is the means for the easy opening of the container.

65 Located within the container is an in-

serted collar 7. This collar is provided with a folded back portion 8. The folded back portion 8 of the collar forms a very rigid section, and this section of the collar is 5 made so that it fits within the body wall so as to frictionally grip the same. The collar is made from a band and the ends joined in any suitable way so as to make it a rigid collar. The collar is sized so that when it 10 is crowded into the body the frictional grip between the collar and the body wall will hold the collar in fixed relation to the body wall. The portion 9 of the collar above the lower score line 4 is inset from the body 15 wall as clearly shown in the drawings, and the upper edge portion of the collar is rolled into a bead 10. The end 2 for closing the container is provided with a depending member 11. This member 11 as shown is 20 formed by drawing the metal. The metal is turned or drawn first in one direction and then in the other so as to form this depending member. This produces an outside slip member for reclosing wherein the lower edge 25 is rounded and smooth and unbroken and there is no danger of cutting the hand by engagement therewith. The portion 9 of the inserted collar attached to the body wall is inset the thickness of the metal and this 30 provides a space between the portion 9 and the body wall which receives the depending member 11, when the container is made and before it is opened.

When the tearing strip 6 is removed the 35 container is practically left in closed condition, that is, the end with its depending member 11 formed integral therewith is down over the inserted collar 10 attached to the body wall. However, the end 2 can be 40 readily slipped off from the container. It can also be again slipped onto the container for reclosure purposes.

While I have shown the member 11 as shaped so that the walls thereof are substantially in contact, it will be understood, of course, that it may be otherwise shaped. The only essential feature is that the inner wall of the member shall have a slip frictional fit with the outer wall of the collar 50 attached to the body of the container. Contact with the portion of the body having the score lines is also helpful in that it forms a support for the tearing strip while it is being torn away. While I have shown this 55 member as formed integral with the end, it will be understood that it may be otherwise formed, but it is essential that it shall be fixed to the end and removable therewith after the tearing strip has been removed. It will be noted that the container 60 after the tearing strip is removed is of precisely the same capacity as when filled and the end 2 attached thereto for the end after the tearing strip is removed retains the same 65 position on the body and when it is placed

thereon for reclosure it also takes the same position on the body.

It is obvious that minor changes in the details of construction may be made without departing from the spirit of the invention as set forth in the appended claims. 70

Having fully described my invention what I claim as new and desire to secure by Letters Patent, is:—

1. An easy opening container, comprising 75 a body having ends seamed thereto, said body having spaced score lines forming a tearing strip for releasing the end from said body, a collar located within the body and attached thereto below the score lines and 80 extending upwardly, the upper portion of the collar being inset from the wall of the body, and a depending member fixed to the upper end and disposed between the collar and the wall of the body making contact with the portion of the body having the score lines and making a removable outside slip contact with said collar when said tearing strip is removed. 85

2. An easy opening container, comprising 90 a body having ends seamed thereto, said body having spaced score lines adjacent the seam joining the upper end to the body and forming a tearing strip for releasing the end from said body, a collar located within the 95 body and attached thereto below the score lines and extending upwardly and terminating substantially at the lower edge of the double seam, the upper portion of the collar being inset from the wall of the body, and a depending member fixed to the upper end and disposed between the collar and the wall of the body making contact with the portion of the body having the score lines and making a removable outside slip contact with 100 said collar when said tearing strip is removed. 105

3. An easy opening container, comprising 110 a body having ends seamed thereto, said body having spaced score lines adjacent the seam joining the upper end to the body and forming a tearing strip for releasing the end from said body, a collar located within the body and attached thereto below the score lines and extending upwardly and terminating 115 substantially at the lower edge of the double seam, the upper portion of the collar being inset from the wall of the body, said end having an integral depending member disposed between the collar and the wall of the body making contact with the portion of the body having the score lines and making a removable outside slip contact with said collar when said tearing strip is removed. 120

4. An easy opening container, comprising 125 a body having ends seamed thereto, said body having spaced score lines adjacent the seam joining the upper end to the body and forming a tearing strip for releasing the end from said body, a collar located within the 130

body and attached thereto below the score lines and extending upwardly and terminating substantially at the lower edge of the double seam, the upper portion of the collar being inset from the wall of the body, said 5 end having a depression forming a vertical wall therein adapted to contact with the portion of the can body having the score lines, said vertical wall being bent back on itself so as to provide a vertical wall forming a removable outside slip contact with the collar when the tearing strip is removed.

In testimony whereof, I affix my signature.
FRANK J. O'BRIEN.
